UNITED STATES PATENT OFFICE.

EMANUEL RICKERSBERG, OF CLEVELAND, OHIO, ASSIGNOR TO THE RICKERSBERG
BRASS COMPANY, OF CLEVELAND, OHIO, A CORPORATION OF OHIO.

ATTACHMENT FOR PLUMBING FIXTURES.

Application filed March 23, 1925. Serial No. 17,475.

This invention relates to attachments for plumbing fixtures and has for its object to provide improved means for supporting a receptacle such as a soap dish or cup holder 5 on a wash bowl.

A further object is to provide a receptacle support adapted to be clamped upon the flat marginal portion of the bowl between the surface of the bowl and a permanent plumb- 10 ing fixture secured thereon.

With the above and other objects in view, the invention may be said to comprise the device as illustrated in the accompanying drawings hereinafter described and particu- 15 larly set forth in the appended claims, together with such variations and modifications thereof as will be apparent to one skilled in the art to which the invention appertains.

Reference should be had to the accompanying drawing forming part of this specification, in which Fig. 1 is a perspective view showing the wash bowl having receptacle supporting attachments, one carrying the soap holder, the other a cup holder, and one clamped between the hot water faucet and the flat marginal portion of the bowl, and the other clamped between the cold water faucet and the bowl; Fig. 2 is a 20 side elevation of the supporting attachment with a soap dish thereon; Fig. 3 is a side elevation partly in section showing the same attachment with a cup holder thereon; Fig. 4 is a plan view of the base member of the receptacle supporting attachment; Fig. 5 is a perspective view showing a supporting attachment carrying a soap dish and clamped upon the bowl by a fixture such as the guide collar of a drain valve actuator; Fig. 6 is a 25 side elevation partly in section showing the modified form of receptacle supporting attachment employed for supporting the receptacle centrally of the bowl.

The present invention is applicable to 45 various forms of wash bowl in which the plumbing fixtures are secured upon a flat marginal portion and is illustrated in the accompanying drawing in connection with a wash bowl 1 of the pedestal type which is provided around the bowl portion with a flat marginal portion 2 upon which are clamped the hot and cold water faucets 3 and 4 and with a fixture 5 between the faucets for the drain valve actuator.

55 Referring to Figs. 1 to 4, the receptacle

supporting attachment has a flat base portion 6 which is provided with an aperture 7 adapted to receive the extension of a faucet which passes through the bowl or to receive the guide sleeve of the valve actuator. The 60 flat base portion 6 has an integral upwardly and outwardly extending arm 8 terminating in a boss 9 which is provided with a vertical bore adapted to receive the reduced lower end portion 10 of a vertical support- 65 post 11 which is adapted to be clamped to the arm 8 by means of a clamping nut 12 upon the threaded lower end of the reduced portion 10 of the post. The post 11 has a threaded upper end 13 upon which the receptacle is detachably secured. The soap dish 14 has a nut 15 embedded in the bottom thereof and centrally disposed with respect to the soap dish by means of which the soap dish may be detachably secured to the upper 70 end of the post. The portion 13 of the post also carries a lock nut 16 which may be screwed into engagement with the nut 15 to lock the soap dish in adjusted position on the post. The soap dish 14 which is preferably 75 rectangular in shape will be supported closely adjacent the wall of the room in which the wash bowl is placed since it is the usual practice to mount the wash stand closely adjacent the wall. The space between the soap dish and wall is usually not sufficient to permit rotation of the soap dish on the post 12 and it is for this reason that the detachable connection is provided between the post 12 and the arm 8. When it is de- 80 sired to remove the soap dish to wash or replace the same, the nut 12 can be unscrewed permitting the post and soap dish to be lifted from the arm 8. After detachment from the arm 8 the soap dish may be readily 85 removed from the post. In assembling the attachment the fixture by which it is clamped to the bowl is removed from the bowl and again secured in place with the base portion 90 95 100 105 110 6 of the attachment clamped between the supporting flange of the fixture and wash bowl. The soap dish is then screwed upon the upper end of the post 12 and the post 12 is then inserted into the boss 9 and clamped in place. The soap dish may then be ad- justed to the desired angular position and locked in such position by means of the lock nut 16.

Exactly the same attachment may be em- 110 ployed for the cup holder 17 which has an

integral nut 18 at the center of its bottom which screws upon the upper end 13 of the post 12 and is engaged by the lock nut 16.

If desired, a receptacle such as a soap dish 5 may be supported by an attachment secured to the flat marginal portion of the bowl by the fixture between the faucets as shown in Fig. 5. The specific form of supporting attachment preferably employed for supporting 10 the soap dish centrally of the wash bowl is shown in detail in Fig. 6. This attachment has a flat apertured base portion 20 similar to the base portion 6 in the modification first described, and integral with the 15 base portion 20 there is an outwardly and upwardly extending arm 21 upon the outer end of which is rigidly secured a vertical supporting post 22. The post 22 has its upper end portion 23 bent back over the base 20 portion and lying in a substantially horizontal plane. The soap dish 14 may be detachably clamped upon the horizontal upper end portion 23 of the post by means of a 25 clamping bolt 24 which passes through the arm 23 and screws into the nut 15 of the soap dish. By unscrewing the nut 24 the soap dish may be removed from the supporting post.

Having described my invention, I claim:

30 1. An attachment for plumbing fixtures comprising a base plate, adapted to rest upon the flat marginal portion of a wash bowl and having an aperture adapted to receive a clamping member passing through 35 the bowl, an arm integral with said base plate and extending outwardly and upwardly therefrom, said arm having a vertical bore at its outer end, a post having a

reduced threaded lower end extending through the bore of the arm and a threaded 40 upper end, a nut on the lower end of the post for clamping the post to the arm, a receptacle supported on the top of the post and having a part in threaded engagement with the post, and a lock nut on the upper 45 threaded end of the post.

2. An attachment for a wash bowl having a flat marginal portion upon which a faucet is clamped comprising a base plate adapted to be clamped between the faucet and bowl, 50 an arm extending laterally from the base plate, a post having a reduced threaded lower end passing through the outer end of the arm, a nut on the lower end of the post for clamping the post to the arm and a 55 receptacle mounted on the post at the upper end thereof.

3. An attachment for a wash bowl having a flat marginal portion upon which a faucet is clamped comprising a flat base plate having an aperture to receive the water pipe to which the faucet is connected and adapted to be clamped between the faucet and bowl, an arm extending laterally from the base plate, a vertical post detachably secured to 65 the outer end of said arm said post having a threaded upper end, a receptacle having a nut fixed to the bottom thereof adjacent the center of the receptacle, and adapted to be screwed onto said post, and a lock nut carried by the post and engageable with the nut on the receptacle to lock the receptacle in adjusted position on the post.

In testimony whereof, I hereunto affix my signature.

EMANUEL RICKERSBERG.
